COMBINED TABLE AND PLANTER

Alfonso P. Molina, 2801 N. Habana Ave., Tampa, Fla.

Filed Apr. 2, 1962, Ser. No. 69,536

Term of patent 14 years

(Cl. D35—3)

I claim:

The ornamental design for a combined table and planter substantially as shown and described.
